US00D808053S

(12) **United States Design Patent** (10) **Patent No.:** **US D808,053 S**
(45) **Date of Patent:** **** Jan. 16, 2018**

(54) **ADJUSTABLE LIGHTING FIXTURE WITH
PIVOTABLE LIGHTING FIXTURE VISOR**

(71) Applicant: **Musco Corporation**, Oskaloosa, IA (US)

(72) Inventors: **Myron Gordin**, Oskaloosa, IA (US); **Steven T. Heaton**, Oskaloosa, IA (US)

(73) Assignee: **Musco Corporation**, Oskaloosa, IA (US)

(**) Term: **15 Years**

(21) Appl. No.: **29/569,380**

(22) Filed: **Jun. 27, 2016**

(51) LOC (11) Cl. **26-03**

(52) U.S. Cl. **D26/63**
USPC ....

(57) **CLAIM**

The ornamental design for an adjustable lighting fixture with pivotable lighting fixture visor, as shown and described.

DESCRIPTION

FIG. 1 is a perspective view of the claimed design in its general operational orientation;

FIG. 2 is an alternative perspective view of the claimed design;

FIG. 3 is another alternative perspective view of the claimed design;

FIG. 4 is another alternative perspective view of the claimed design;

FIG. 5 is a front elevation view of FIG. 1;

FIG. 6 is a back elevation view of FIG. 1;

FIG. 7 is a right side elevation view of FIG. 1;

FIG. 8 is a left side elevation view of FIG. 1;

FIG. 9 is a top plan view of FIG. 1;

FIG. 10 is a bottom plan view of FIG. 1;

FIG. 11 is a sectional view taken along cut line A-A of FIG. 5 illustrating for clarity the elements of the claimed design; and,

FIG. 12 is a partially exploded view of FIG. 1 illustrating for clarity the elements of the claimed design.

The broken lines shown in the drawings illustrating unclaimed portions of the adjustable lighting fixture with pivotable lighting fixture visor form no part of the claimed design.

1 Claim, 12 Drawing Sheets
